US0D1052565S

(12) **United States Design Patent** (10) **Patent No.:** **US D1,052,565 S**
(45) **Date of Patent:** **** Nov. 26, 2024**

(54) **COVER WINDOW**

(71) Applicant: **Samsung Display Co., Ltd.**, Yongin-si (KR)

(72) Inventors: **Seung Kim**, Seongnam-si (KR); **Byung Hoon Kang**, Hwaseong-si (KR); **Kyung Rok Ko**, Suwon-si (KR); **Seung Ho Kim**, Asan-si (KR); **Young-Seok Seo**, Seoul (KR); **Gyu In Shim**, Yongin-si (KR); **Jeong Ho Hwang**, Cheonan-si (KR); **Young Su Kim**, Gunpo-si (KR); **Jae Suk Yoo**, Seoul (KR); **Yong Won Yun**, Yongin-si (KR); **Jeong-Seop Choi**, Cheonan-si (KR)

(73) Assignee: **Samsung Display Co., Ltd.**, Yongin-si (KR)

(**) Term: **15 Years**

(21) Appl. No.: **29/783,138**

(22) Filed: **May 11, 2021**

(57) **CLAIM**

The ornamental design for a cover window, as shown and described.

DESCRIPTION

FIG. 1 is a front perspective view of the cover window showing our new design according to a first embodiment; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a rear perspective view thereof;

FIG. 9 is a front perspective view of the cover window showing our new design according to a second embodiment;

FIG. 10 is a front view thereof;

FIG. 11 is a rear view thereof;

FIG. 12 is a left side view thereof;

FIG. 13 is a right side view thereof;

FIG. 14 is a top view thereof;

FIG. 15 is a bottom view thereof; and

FIG. 16 is a rear perspective view thereof;

(Continued)

FIG. 17 is a front perspective view of the cover window showing our new design according to a third embodiment; FIG. 18 is a front view thereof; FIG. 19 is a rear view thereof; FIG. 20 is a left side view thereof; FIG. 21 is a right side view thereof; FIG. 22 is a top view thereof; FIG. 23 is a bottom view thereof; and FIG. 24 is a rear perspective view thereof; FIG. 25 is a front perspective view of the cover window showing our new design according to a fourth embodiment; FIG. 26 is a front view thereof; FIG. 27 is a rear view thereof; FIG. 28 is a left side view thereof; FIG. 29 is a right side view thereof; FIG. 30 is a top view thereof; FIG. 31 is a bottom view thereof; and, FIG. 32 is a rear perspective view thereof.
